Primary Examiner — Gino Colan(74) *Attorney, Agent, or Firm* — Armstrong Teasdale LLP(57) **CLAIM**

We claim the ornamental design for a check valve, as shown and described.

DESCRIPTION

FIG. 1 is a perspective view of a check valve showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures are for the purpose of illustrating portions of the check valve which form no part of the claimed design.
